METHOD AND APPARATUS FOR DISTILLATION OF HYDROCARBONS

Clare D. Gard, Los Angeles, Calif., assignor to
Union Oil Company of California, Los Angeles,
Calif., a corporation of California

Application May 30, 1930. Serial No. 457,656

5 Claims. (Cl. 196—85)

This invention relates to distillation method and apparatus, and is directed more particularly to steam distillation of oil in which the steam is directly introduced into the oil and the oil is agitated thereby.

5 I have found that while operating either at constant or increasing temperatures it is highly advantageous to keep the oil and the steam in constant and adequate contact in order to vaporize the maximum percentage of oil vaporizable under the conditions employed.

10 A difficulty is ordinarily encountered in the distillation of oil due to the fact that the lighter vapors volatilized from the oil body carry over oil fractions heavier than those desired in that particular cut. Also, the unvolatilized oil remaining in the still may yet contain lighter oil fractions which desirably should be distilled over with the other vapors. I have found that 15 by refluxing undesirable heavy oils back into the oil body and by contacting the oil bottoms with vapors rising from the oil body, the vapors are freed substantially of undesirable heavy components and the bottoms are freed substantially 20 of lighter products which are desired in vapor form.

An object of this invention is to provide means for steam distillation whereby the oil being distilled is in constant and adequate contact with 25 the steam employed as a distillation aid, either at a constant temperature or at increasing temperatures. An additional object is to provide means for the return of reflux and the circulation of still bottoms. All of these objects are 30 for the purpose of distilling oil to obtain vapors free from undesirable heavy fractions and to insure total vaporization of all fractions desired in the vapor state without the danger of local overheating.

35 More specifically stated, the invention comprises a distilling apparatus including an oil still adapted to hold a body of oil and containing two concentric steam pipes wound vertically to form baffles which act to direct the course of oil currents produced by steam which is injected into the oil body. The invention further includes means for introducing steam directly into the oil confined within the space defined by the inner heating coil and also into the oil confined 40 within the annular space between the inner heating coil and the outer heating coil. The invention further comprises a steam distillation apparatus in which reflux condensate obtained from the vapors rising from the oil body and/or unvolatilized oil obtained from the oil bottoms

may be caused to re-enter into the oil body maintained in circulation by means of the aforesaid baffles and steam. The invention also comprises the method of distillation wherein currents within the oil body are induced by flow 45 of steam therethrough and wherein the said currents are changed in direction by a second stream of steam, the oil meanwhile being heated by contact with internal heating means.

50 In the accompanying drawing wherein a preferred embodiment of the invention is disclosed by way of illustration:

Fig. 1 is a vertical section showing an oil distillation column constructed according to the 55 present invention; and

Figs. 2 and 3 are cross-sections through the distillation column and are taken respectively along lines 2—2 and 3—3 of Fig. 1.

60 Referring to the drawing, numeral 1 represents a shell of a vertical still connected with oil conducting pipe 2 which branches into inlet pipe 3 controlled by valve 4 and inlet pipe 5 controlled by valve 6. Still 1 is further provided with vapor outlet 9 controlled by valve 10 and residuum outlet 11 controlled by valve 12. Below the normal oil level A—A, are situated two concentric 65 vertically wound heating coils, 16 and 21, respectively, through which heating fluid such as steam is caused to pass. The inner heating coil 16 having steam inlet 17 controlled by valve 18 and outlet 19 controlled by valve 20 comprises a pipe 70 vertically coiled to form a baffle which acts to direct the course of oil currents produced by steam entering through jet 30 to be described below. Coil 16 may be tightly wound in order to 75 form a substantially solid cylindrical wall, or it may not be necessary to wind it as tight as this. In either event, it must be given a conformation sufficient to form a baffle for the purpose of directing oil currents in the body of oil in a manner to 80 be described below.

The outer heating coil 21 comprises steam inlet pipe 24 controlled by valve 25 and outlet 26 controlled by valve 27. Heating coil 21 may be more loosely wound than coil 16 in order to allow at 85 least a partial flow of oil between the coils. Steam jet 30 in its preferred form is shown in detail in Fig. 3. It comprises two concentric pipes 31 and 32 connected by pipes 33. Steam inlet 34 controlled by valve 35 connects with the inner pipe 32 which is perforated on its upper side. Outer pipe 31 is likewise perforated. The perforations on the inner jet are so arranged that steam jetting from them will pass through approximately the 90 middle area of the cylindrical space outlined by 95

the inner coil 16. The perforations of the outer jet are so arranged that steam jetting from them will pass into the annular space confined between inner coil 16 and outer coil 21. If desired, outer pipe 31 and inner pipe 32 may be provided with 5 separate and individual valve controlled steam inlets whereby the separate currents of steam entering the oil through the perforations in said pipes 31 and 32 respectively can be individually controlled. If additionally desired, either one of these streams of steam may be totally shut off depending upon the exigencies in the distillation of any particular oil.

10 The upper portion of still 1 comprises a reflux section containing reflux plates 40 provided with bubble caps 41 and overflow pipes 42 disposed in the usual manner. The bottom overflow pipe 43 may extend to a point above oil level A—A or it may depend into the oil body in the manner 15 shown. Deflector 44 is provided in order to give the desired directional flow to the incoming oil. For circulating the oil bottoms, pipe 50 is provided, connected with still 1 near the bottom thereof and also with the refluxing section there- 20 of. In order to circulate the oil from the bottom of the still through line 50 back into the still, there is provided steam or oil inlet 51 terminating in injector 53 situated within recirculation line 50. The flow of injecting fluid is controlled by 25 valve 52.

30 In employing this system for the distillation of oil, still 1 is filled with oil to the level A—A, main- tained during the course of the operation. The oil may enter from a source not shown through 35 pipes 2, 3 and 5, valves 4 and 6 being open. Steam or other heating fluid is passed through heating coils 16 and 21, the steam entering through inlets 17 and 24, respectively and leaving the coils through outlets 19 and 26, respectively. Steam is 40 also introduced directly into the oil through jet

45 30. The steam which is jetted through the perforations in pipe 32, situated in approximately the middle of the area defined by the cylindrical coil of heating tubes 16, creates an upward current of oil in the middle thereof and a corresponding downward movement close to heating coil 16, whereby the oil is thoroughly contacted with the heating means. This downward flowing current of oil within the oil body then causes the oil to 50 flow below coil 16. The ascending current of steam ejected from the perforations in the upper part of outer steam pipe 31 which is situated so that the steam flows between the inner heating coils 16 and the outer heating coils 21 assists in 55 drawing the oil from the inner chamber into the annular chamber between coils 16 and 21. The jetting action last mentioned thereby reverses the flow of the oil in the oil body and causes an upward circulation which forces the oil between the coils 21. When perforated pipes 31 and 32 are 60 provided with separate and individual valve-con- trolled steam inlets the separate currents of steam entering the oil through said perforations can be individually controlled. If desired either one of 65 these streams of steam may be shut off depending upon the requirements in the distillation of any particular oil. Due to the prolonged and intimate contact between the oil, the steam and the heating coils, a uniformity of temperature 70 may be maintained within the oil body and a maximum of products desired in the vapor state may be volatilized therefrom without danger of local overheating.

75 As the oil is volatilized, the vapors pass up- wardly through the bubble caps 41 situated on

the reflux plates 40 in the usual manner. Fresh oil may be continuously introduced into still 1 through pipe 2, and by proper manipulation of valves 4 and 6 in pipes 3 and 5 the stream may be caused to enter upon either or both of the reflux plates 40 above which these inlets are directly situated, depending upon the degree of refluxing desired. The fresh oil and reflux condensed from the vapors flow downwardly from the reflux plates 40 through overflow pipes 42 in counter-current with ascending vapors in the usual manner. The oil on the lowest reflux plate 40 is then directed downwardly through overflow pipe 43. If the latter does not depend into the body of oil, the oil descending therethrough merely drops upon the surface of the oil. It is preferable, however, to provide deflector 44 situated below the oil level into which the overflow pipe 43 extends. The oil flowing therein is deflected close to the inner side of inner heating coils 16, thereby aiding in the circulation of the oil body as previously de- 80 scribed. Other types of deflectors may be pro- 85 vided without departing from the spirit of the in- vention.

90 The oil bottoms may still contain some lighter fractions which it is desired should be vaporized. In order to accomplish the total vaporization of these lighter fractions, the bottoms are recirculated by passage upwardly through pipe 50 back into the refluxing section of the still. In 95 order to force the oil from the bottom of the still upwardly through pipe 50 back into the still, steam or the like may be injected into vertical pipe 50 through injector 53 connected with steam supply pipe 51 controlled by valve 52. In place 100 of steam, a portion of the oil charge may be fed into the still 1 through line 51 and injector 53. The same result is thereby produced, i. e. lifting the oil bottoms through pipe 50 for re- 105 circulation.

110 Due to the scrubbing action on the vapors within the refluxing zone previously described, heavy undesirable constituents will be removed from the vapors and will be refluxed into the oil body. Due to the recirculation of the oil bot- 115 mands and to the constant and adequate contact of the oil, steam, and heating coils, as previously described, substantially all of the products de- 120 sired in the vapor state will be volatilized from the oil. Vapors from the still pass through pipe 125 9 controlled by valve 10 into suitable condensers or the like, not shown. Residuum from still 1 exits through pipe 11 controlled by valve 12 to suitable storage or the like, not shown.

130 The pressures and temperatures employed in this device depend entirely upon the character of the oil stock introduced into the still and the boiling points of the fractions which are to be separated by the distillation. The amount of refluxing is likewise dependent upon these con- 135 ditions.

140 It is to be understood that the above disclosures are considered merely as illustrative and not as limiting, since many variations may be made within the scope of the following claims.

I claim:

145 1. In oil distillation apparatus, a vertically dis- posed, closely wound heating coil defining a dis- tillation chamber and additionally functioning as a current directing baffle, a second heating coil, spaced from and disposed around said first men- tioned coil, and means to induce circulation of the oil undergoing distillation in such a manner that oil within the distillation chamber is caused to flow downwardly along the inner periphery 150

- of the closely wound coil and thence upwardly between the two coils.
2. In distillation apparatus, a vertically disposed, closely wound heating coil defining a distillation chamber and additionally functioning as a current directing baffle, a second heating coil, spaced from and disposed around said first mentioned coil, means for injecting steam into the distillation chamber so that the oil undergoing distillation is caused to flow downwardly along the inner periphery of the closely wound coil and thence upwardly between the two coils. 80
- 5 3. In distillation apparatus, a vertically disposed, closely wound heating coil defining a distillation chamber and additionally functioning as a current directing baffle, a second heating coil, spaced from and disposed around said first mentioned coil, and means for injecting steam into the space between the two coils so that the oil undergoing distillation is caused to flow downwardly along the inner periphery of the closely wound coil and thence upwardly between the two coils. 85
- 10 4. In distillation apparatus, a vertically disposed, closely wound heating coil defining a distillation chamber and additionally functioning as a current directing baffle, a second heating coil, spaced from and disposed around said first mentioned coil, and means for injecting steam into the space between the two coils so that the oil undergoing distillation is caused to flow downwardly along the inner periphery of the closely wound coil and thence upwardly between the two coils. 90
- 15 5. A method of steam distilling oil without substantial cracking thereof comprising inducing a down-flowing current of oil along the periphery of a heating coil and within a body of oil by an ascending stream of steam, deflecting the direction of said down-flowing current by a second, ascending stream of steam so that the oil is caused to flow upwardly between the first mentioned coil and a second coil annularly disposed with respect to the first coil, and flowing heating fluid through said coil to heat the oil during its downward and upward courses. 95
